CONTROLLING MEANS FOR VALVES

Fred C. Arey, Oak Park, Ill., and De Los E. Hibner, Jr., Dubois, Pa., assignors to Vulcan Soot Blower Corporation, a corporation of Pennsylvania

Application May 20, 1933, Serial No. 671,950

1. Claim. (Cl. 251—133)

In our application, Serial Number 671,951, we have disclosed a head for a soot blower in which, upon operating a suitable actuator as, for example, a chain, the tubular cleaning element is turned step by step and at the same time a main valve is opened to admit steam to the cleaning element, the opening and closing of the main valve being controlled by a pilot valve which is operated in one direction by said actuator and in the other direction by pressure of the steam in the head. The object of the present invention is to modify the controlling means for a head of this character, so that the pilot valve may be controlled by simple mechanism independently of the means for effecting a turning movement of the cleaning element.

In carrying out our invention, we employ separate actuators for the cleaning element and the pilot valve. The cleaning element may, for example, be operated by the same means as in the aforesaid application, whereas the controlling means for the pilot valve should be such that, after the pilot valve has been shifted into the position for causing the main valve to open, it will remain in that position without further attention on the part of the operator, until it is again desired to shut off the steam or other cleaning fluid from the cleaning element. Therefore, it is not only possible to permit the cleaning fluid to flow through the cleaning element before the latter begins to rotate, or at the end of a completed cycle of step by step movements, but the operator may devote his entire attention to the turning of the cleaning element after the steam or other cleaning fluid has once been turned on. Therefore, viewed in one of its aspects, the present invention may be said to have for its object to produce a simple and novel controlling mechanism for a pilot valve or the like which will move the valve into a working position and then hold it there without further aid on the part of the operator until such a time as it is desired that the position of the valve be changed.

The various features of novelty whereby our invention is characterized will hereinafter be pointed out with particularity in the claim; but, for a full understanding of the invention and of its objects and advantages, reference may be had to the following detailed description taken in connection with the accompanying drawings, wherein:

Figure 1 is a side elevation of a head equipped in accordance with the present invention, a view of the parts being shown in section; Fig. 2 is a section on line 2—2 of Fig. 1; Fig. 3 is a section,

on an enlarged scale, on line 3—3 of Fig. 2, only a small fragment of the head in the vicinity of the valve casing being shown; Fig. 4 is a view similar to Fig. 3, showing the parts in different positions than in Fig. 3; and Fig. 5 is an elevation of the inner side of the chain pulley shown in Fig. 2, or a section on line 3—3, looking in the opposite direction from that in which the arrows point, showing only the pulley.

Referring to the drawings, 1 represents a hollow head to which is connected and from which extends a rotatable tubular cleaning element 2. This element may be turned step by step, or otherwise, by suitable mechanism housed within a casing 3, the actuating means for such mechanism being conveniently a shaft 4 having on the outer end a sprocket wheel or pulley 5 upon which hangs a sprocket chain 6. These parts of themselves form no part of the present invention and the driving mechanism for turning the cleaning element may be like that disclosed in the prior application of Fred C. Arey, Serial Number 640,373.

Aside from the mechanism for turning the tubular cleaning element, the head is preferably of the type disclosed in the application of Fred C. Arey, Serial Number 604,382, in which steam may enter the cleaning element when a main valve in the head is opened and is shut off when said main valve is closed, the main valve being controlled by a small pilot valve. The pilot valve is held in one of its two extreme positions by the pressure of the steam in the head and must be moved into its second position, against the pressure of such steam, by a suitable actuator. The main valve remains open while the pilot valve remains in said second position. In this last mentioned application the pilot valve is forced into its second position by a device actuated by the sprocket wheel or pulley that serves to turn the cleaning element.

In the present construction there is shown only the stem 7 of the pilot valve; this stem projecting a considerable distance when the pilot valve is in its main valve-closing position and receding into its casing as the pilot valve is forced into its other position; these two positions of the stem being respectively indicated in Figs. 3 and 4. However, instead of controlling this valve stem through the operation of the sprocket wheel or pulley 5, we provide independent actuating means. In the arrangement shown, there is a bell crank lever having a short arm 8 and a long arm 9, journaled at the angle or elbow upon a stationary pin 10 fixed to the head. The axis of the pin 10

is at right angles to the valve stem, and its position relatively to the valve stem is otherwise such that, when the bell crank lever is oscillated, the short arm thereof swings in a plane containing the axis of the valve stem; at one point in its movement engages with the end of the valve stem; and thereafter, as the movement of the lever continues, forces the valve stem back into the valve casing.

10 The bell crank lever is adapted to be oscillated or rocked by a sprocket wheel or pulley 12 supported on the head for angular movements about an axis parallel to the axis of the pin or journal 10 and near the lever. On the inner side of this wheel or pulley are a hub 13 and a boss 14 beside the hub. Extending between the boss 14 and the free end of the long arm of the bell crank lever is a curved link 15, the curvature of whose concave edge is that of a circle of about the same diameter as the hub 13. The link is hinged to the bell crank lever by a suitable pin 16 and to the boss 14 by a suitable pin 17 fixed to the boss and projecting through a hole in the link. With this arrangement, when the wheel or pulley 12 is turned in one direction, the long arm of the bell crank lever is drawn down close to the hub 13 and the curved link is brought into a position in which the hub fits in the concave side or edge of the link, as shown in Fig. 3. Any further movement of the wheel or pulley in this same direction, which is the clockwise direction as viewed in Fig. 3, is prevented after such engagement between the link and the hub is effected. At this time, however, the short arm of the bell crank lever has swung out far enough to be free from the valve stem which may then be forced outwardly by the steam behind it. When it is desired to shift the pilot valve by pushing the stem thereof in, the sprocket wheel or pulley 12 is turned in the counter-clockwise direction as viewed in Fig. 3, causing the link to act as a strut to push the free end of the long arm of the bell crank lever up. As the upward swinging movement of the long arm of the bell crank lever progresses, the short arm moves into engagement with the end of the valve stem and pushes the stem in. Somewhat before the inward movement of the valve stem is completed, the pin 17 moves across the line connecting the center of the pin 16 with the center of the hub 13, so that the hub and boss 14 on the one side, and the link 15 on the other side, constitute a toggle which must be straightened before they can be swung back to the starting position shown in Fig. 3.

55 However, the steam pressure behind the valve stem is now acting on the lever in a direction which causes the toggle to be held against

straightening. It will be seen that, since the joint between the links of the toggle has passed beyond center, the thrust of the bell crank lever is not only in a direction to prevent straightening of the toggle, but is actually in a direction to produce further counter-clockwise movement of the members 13 and 14 and, therefore, of the wheel or pulley 12. To prevent such further movement, we provide a stop between the link 15 and some part of the wheel or pulley. In the arrangement shown, the wheel or pulley has on the inner side a lug 18 which engages with the rear or trailing edge of the link 15 when the parts have been brought into the position shown in Fig. 4. The lug 18 is approximately twice as far away from the center of the wheel as is the pin 17, and therefore the link 15 cannot push the wheel or pulley around, because it cannot get out of the way of the lug 18. In other words, the parts being in the positions to lock the valve stem in, as indicated in Fig. 4, the pressure of the steam tending to push the valve stem out serves to maintain the parts in these locking positions until the operating wheel therefor has been turned through a sufficient angle in the clockwise direction to carry the pin 17 back across the line connecting the axis of the pin 16 and the center of the wheel or hub.

While we have illustrated and described with particularity only a single preferred form of our invention, we do not desire to be limited to the exact structural details thus illustrated and described; but intend to cover all forms and arrangements which come within the definitions of our invention constituting the appended claim.

We claim:

The combination with a valve element, of a lever for moving said element into a predetermined position, a rotatable wheel having a hub, a curved link connected at one end to the lever and extending around the hub of the wheel to the opposite side of the hub from that on which the joint between the link and the lever lies while the lever is in its idle position, the parts being so proportioned that upon rotation of the wheel to cause the valve element to be moved into said predetermined position the point of connection between the link and the wheel passes to the same side of the hub as that on which the joint between the link and the lever lies and then past a line connecting said joint with the center of the wheel, and a lug on the wheel moving into engagement with the link upon the shifting of the valve element into said predetermined position.
